JAR COVER

Charles S. Baron, Tiffin, Ohio

Application October 6, 1933, Serial No. 692,524

2 Claims. (Cl. 215—38)

My present invention relates generally to containers and covers for the same, and has for its object a jar, bottle, or the like, which may be made of any suitable material, such, for example, as glass, earthen ware, or metal if desired. The shape and configuration of the jar are susceptible of wide variation in respect to design and dimensions. The cover may be solid, as for the confinement of liquid within the jar, or it may be foraminously perforate for use as a container for table service of pulverulent substances, such as salt, pepper, or spices.

The means for securing the cover to the jar are very simple, so as to render the jar and its cover easy to be effectively secured together for use, or to be separated upon occasion as required, by the simplest disjunctive manipulation, without the necessity for imparting to the respective members any relative motion by twisting or screwing movement of the two portions, which, when united, complete the container, such movement being sometimes difficult to effect.

In addition to the device comprising only a cover and jar, provision is made for the accommodation between them, in assembled union, of a liner, which may be made of any suitable elastic or semi-elastic yielding material, varying, for instance, from thin glazed paper or thicker cardboard to the more substantial thickness of a cork liner, which is especially adapted for hermetically sealing the complete container against leakage of liquid confined therein. The liner may be of disk shape, or for some purposes, it may be desirable to make it in the familiar shape of an annular gasket.

What constitutes my invention will be herein-after described in detail and succinctly defined in the appended claims.

In the accompanying drawing which illustrates my invention in its present preferred form of embodiment,

Figure I is a diametrical vertical section of the neck of a jar and of its attached cover in one form of embodiment.

Figure II is a similar view showing a modification of the cover.

Figure III is a like view of a further modification illustrative of a disk shaped liner between the jar and cover.

Figure IV is a view similar to those preceding, showing a reversal between the connective elements on the jar and cover, respectively.

Figure V is a top view of the cover shown in Figure I, illustrating in broken line the expandability of the cover by which the union and dis-

union between the jar and its cover are effected.

Figure VI is a top plan view of jar as shown in Figure I, with cover removed.

Referring to the numerals on the drawing, in which each part is designated by a distinctive numeral, 1 indicates a hollow body which may be made of any suitable material, as aforesaid, and of any design and dimensions preferred. The dimension of the member 1 may vary from the smallest size that may be desirable to sizes 10 as large as four or five inches in the diameter of the neck 2 thereof.

In all dimensions of the member 1, the neck is provided substantially on opposite sides with a pair of latches 3 formed by any preferred method 15 of the material of which the neck is composed. I prefer to locate the latches upon the outside of the neck, but it is obvious that they may be located, mutatis mutandis, on the outside wall of the cap. When located on the outside of the 20 neck, the cap or cover 4 is made as indicated in the drawing, to receive the neck within it; but if the latches be located on the outer wall of the cap and the continuous flange be on the inside of the neck, the skirt of the cover becomes the 25 male member and the neck the female.

I illustrate four forms of female covers, which respectively present advantages in design as well as in mechanical adaptation to the purpose intended. In Figure I for example, the cap 4 is 30 shown in form preferred for solid caps, and which is sufficiently constricted in diameter to define a shoulder 5 between the skirt 6 and the top 7 of the cap, that is adapted to press upon the mouth-defining rim 8 of the jar.

Figure II illustrates a similar form of cap which is preferred for a foraminous cover.

Figure III illustrates a form of cap especially adapted to accommodate within it the thickness of a liner 9 made of such substantial material as 40 cork.

Figure II shows a cap which is distinguished by the presence of a dome-shaped top 10. This form of cap is for some reasons superior to all others, but it requires that the rim 8 be extended sufficiently to find a seat directly against the lined inner face of the dome 10 instead of against the shoulder 5 that is provided in the other caps for such a seat.

Figure III shows a flat topped cover specially 50 adapted to accommodate a heavy liner 9, the rim 8 being omitted.

In Figure V, I show diagrammatically the oval or elongated form which the skirt 6 assumes in comparison with the normal cylindrical shape of 55

the skirt as shown in said figure upon elongation thereof as by action of the latches 3, or by external pressure upon the skirt 6 which accomplishes the same effect.

5. In practice, all that is necessary to secure any form of cap to the body 1 is to force the cap gently into place against the resistance opposed by the presence of the latches 3. Thereupon the skirt assumes at first the elongated form shown in
10. Figure V. The latches are usually located above the rim or annular projection 8 on the neck 2 and the faces of each are tapered from bottom to top as indicated by the numeral 14. Each is provided with an undercut recess 15 into which a
15. projection 16 on the skirt enters when the latter is forced into contact with the bead 8, the resiliency of the skirt causing the member 16 to snap into secure engagement with the wall of the recess and so to confine the cap to the body
20. against accidental displacement in ordinary use. As illustrated, the projection 16 is susceptible of considerable modification of shape in cross-section. For effecting the greatest security of union between the jar and cover, the sharply deformed
25. annular construction of the member 16, as shown, for example only, in Figure IV, is preferred.

As often as occasion may require, the cap may be pulled apart from the body by the gentle application of force which may be facilitated by pressure of thumb and finger applied to opposite sides of the outside of the skirt between the spaces which separate the latches.

What I claim is:

1. In combination with a container, of a deformable cap provided with a resilient circular shaped skirt arranged to detachably engage the container, said skirt being of a uniform depth and having an annular continuous inturned projection adjacent its bottom edge, said projection

completely surrounding the container when the cap is applied, and a pair of diametrically opposed locking members on the container for elongating the diameter of the skirt from its normal circular shape to a substantial oval shape to cause the in-turned projections to yieldably engage the locking members after the cap has been applied to the container, said skirt being sufficiently spaced from the container between the locking members to permit the portions of the skirt disposed between the locking members to be pressed inwardly and the skirt portions opposite the locking members thereby sprung outwardly sufficiently to clear the locking members so that the cap may be readily removed from the container upon the application of inward pressure to opposite sides of the skirt between said locking members.

2. In combination with a container, of a deformable cap provided with a resilient circular shaped skirt arranged to detachably engage the container, said skirt being of a uniform depth and having an annular continuous inturned projection adjacent its bottom edge, said projection completely surrounding the container when the cap is applied, said container having a pair of diametrically opposed tapered latches, each latch being provided with an undercut recess for receiving the projections when the cap is applied to the container, said skirt being sufficiently spaced from the container between the latches to permit the portions of the skirt disposed between the latches to be pressed inwardly and the skirt portions opposite the latches thereby sprung outwardly sufficiently to clear the latches whereby said cap may be readily removed from the container upon the application of inward pressure to opposite sides of the skirt between said latches.

CHARLES S. BARON.
